United States Patent Office

Des. 183,974
Patented Nov. 25, 1958

183,974

INFLATABLE ACTION TOY

William Z. Norman, Flushing, and Julius Billig, New York, N. Y., assignors to Bilnor Corp., Brooklyn, N. Y., a corporation of New York

Application April 23, 1958, Serial No. 50,585

Term of patent 14 years

(Cl. D34—15)

FIG. 2

FIG. 1

Fig. 1 is a side elevational view of an inflatable action toy, showing my new design;

Fig. 2 is a top plan view;

Fig. 3 is a bottom plan view;

Fig. 4 is a front elevational view; and

Fig. 5 is a rear elevational view thereof.

We claim:

The ornamental design for an inflatable action toy, as shown.
